His Attorney

UNITED STATES PATENT OFFICE.

ERNST J. BERG, OF SCHENECTADY, NEW YORK, ASSIGNOR TO GENERAL ELECTRIC COMPANY, A CORPORATION OF NEW YORK.

WIRELESS RECEIVING APPARATUS.

1,352,242.

Specification of Letters Patent.

Patented Sept. 7, 1920.

Application filed February 13, 1917. Serial No. 148,400.

To all whom it may concern:

Be it known that I, ERNST J. BERG, a citizen of the United States, residing at Schenectady, county of Schenectady, in the 5 State of New York, have invented certain new and useful Improvements in Wireless Receiving Apparatus, of which the following is a specification.

My present invention relates to wireless 10 signaling systems and more particularly to means for receiving signals produced by electromagnetic waves radiated from a distant point.

The object of my invention is to provide 15 a simple, cheap and efficient receiving apparatus which will not require the use of the large and expensive antenna ordinarily used for this purpose.

A further object of my invention is to 20 provide a receiving apparatus which will be capable of receiving signals from a certain desired direction to the exclusion of signals and "strays" coming from other directions.

25 The novel features which I believe to be characteristic of my invention are set forth with particularity in the appended claims. The invention itself, however, both as to its organization and mode of operation will 30 best be understood by reference to the following description when taken in connection with the accompanying drawing in which I have indicated, partly in diagram, one embodiment of my invention.

35 As indicated in the drawing my receiving apparatus comprises a coil 1 made up of a large number of turns of insulated wire. Within this coil and at right angles to the plane of the coil I place a number of sheets of 40 copper 2, or other metal having good conductivity. These metal sheets are supported in a framework 3 which is mounted upon the rotatable standard 5 having a handle 6 upon its end whereby the entire structure may be 45 rotated in a horizontal plane. I have shown the coil 1 as being supported directly by the copper sheets 2 but the turns of this coil may be mounted upon a separate form if desired, the only essential feature of the construction being that it shall be positioned at 50 a right angle to the copper sheets. The terminals 7 and 8 of the coil 1 are connected to the grid 9 and cathode 10 of a receiving device 11 of the audion type and the signals 55 to be received will cause a response in the

telephone receiver 12 which is included in a circuit which comprises the cathode 10, anode 13 and a local battery 14. The telephone receivers are preferably shunted by a condenser 15 which serves as a by-path for 60 the radio frequency component of the current flowing in the circuit. A variable condenser 16 serves to tune the receiving circuit to the frequency of the waves to be received and a condenser 17 in series with the grid 9 65 may be employed to assist the device 11 in its action as a detector.

The operation of my receiving apparatus is as follows: If the signal which is to be received comes from a direction in the plane 70 of the coil 1 there will at any given instant be a certain phase difference between the waves cutting the two sides of the coil. Because of this a resultant electromotive force will be set up in the coil, which electromotive force will be applied to the grid 75 of the receiving device and will produce an indication in the telephone receiver. If a wave comes from a direction at right angles to the plane of the coil the waves cutting the 80 two sides of the coil will always be in phase and no resultant electromotive force will be set up in the coil. It will be apparent that if the coil is rotated from a position where it is at right angles to the direction of the 85 received waves toward a position where it is parallel to their direction that an electromotive force will be produced in the coil which increases in magnitude as the phase difference between the waves cutting the two sides 90 of the coils increases until the point is reached where this phase difference is greatest and that this condition will occur when the coil is parallel to the direction of the received waves. Hence by rotating the coil 95 until the point is reached where the received signals are strongest it will be possible to determine with a considerable degree of accuracy the direction from which the received signals come.

100 The metal sheets 2 are in effect short circuited coils of low impedance, and in fact if desired may be replaced by actual coils of low impedance. Electromagnetic waves coming from the desired direction will pass 105 through these sheets without producing any currents therein, since they are at right angles to the direction of the waves and hence without any loss of energy. Signals or strays coming from other directions, how- 110

ever, will produce currents in these sheets. They will also of course tend to produce currents in coil 1. Because of the comparatively low impedance of the sheets, and the 5 high impedance of coil 1 for any waves except those for which it is tuned, most of the energy of the undesirable waves will be dissipated in the sheets and their effect in the coil 1 will be so small that it will not interfere with the reception of the desired waves.

What I claim as new and desire to secure by Letters Patent of the United States is:

1. The method of directive receiving of wireless signals by means of a receiving coil 15 which consists in utilizing said coil as a receiving antenna, rotating the coil in a horizontal plane until the response in receiving apparatus connected thereto is a maximum for the desired signals and at the same time 20 absorbing the energy of undesirable impulses of all frequencies in such a way that they will produce substantially no effect in the receiving coil.

2. The method of directive receiving of 25 wireless signals by means of a receiving coil

which consists in utilizing said coil as a receiving antenna, rotating the coil in a horizontal plane until the response in receiving apparatus connected thereto is a maximum for signals coming from a desired direction 30 and at the same time absorbing the energy of signal impulses of all frequencies coming from other directions in such a way that they will produce substantially no effect in the receiving coil.

3. The method of directive receiving of wireless signals by means of a receiving coil which consists in utilizing said coil as a receiving antenna, rotating the coil in a horizontal plane until the response in receiving 40 apparatus connected thereto is a maximum for signals coming from a desired direction and at the same time absorbing the energy of signal impulses of all frequencies coming from other directions in low impedance 45 circuits which are so located that they are substantially unaffected by the desired signals.

In witness whereof I have hereunto set my hand this 12th day of February, 1917.

ERNST J. BERG.
